UNITED STATES PATENT OFFICE.

WILLIAM A. L. SCHAEFER, OF CHICAGO, ILLINOIS, ASSIGNOR TO JOINTLESS FIRE-
BRICK CO., OF CHICAGO, ILLINOIS, A CORPORATION OF ILLINOIS.

WALL CONSTRUCTION.

Application filed December 11, 1922. Serial No. 606,182.

To all whom it may concern:

Be it known that I, WILLIAM A. L. SCHAEFER, a citizen of the United States, residing at Chicago, in the county of Cook, and State 5 of Illinois, have invented a certain new and useful Improvement in Wall Construction, of which the following is a full, clear, concise, and exact description, reference being had to the accompanying drawings, forming 10 a part of this specification.

My invention relates to improvements in wall construction and more particularly to improvements in the construction of walls which are subjected to intense heating and to 15 fluctuating temperatures such as the walls of boiler settings, furnaces and the like.

The resulting expansion and contraction in walls of this sort has heretofore caused cracking, breaking and the opening of 20 crevices which permit leakage and cause rapid disintegration. In the baffle wall of a tubular boiler this difficulty is increased by expansion, contraction and sagging of the 25 boiler tubes.

An object of my invention is to avoid such cracking, breaking and crumpling and to prolong the life of walls of this sort.

Another object is the provision of an improved method of anchoring such walls.

Another object is the provision of an improved joint that will permit expansion 30 without injury.

Another object is the provision of an effective yet simple and inexpensive joint and 35 method to this end.

Another object is the provision of a joint which will not only permit expansion and contraction without injury but will permit sagging of the boiler tubes as well.

Further objects and advantages of the 40 invention will become apparent as this description proceeds.

In the accompanying drawings—

Figure 1 is a more or less diagrammatic 45 longitudinal section through a boiler section showing an embodiment of my invention in connection therewith; and

Figure 2 is an enlarged detailed section 50 showing another embodiment of the invention.

Although not limited to that particular purpose, in the embodiment selected for illustration I have shown the invention as employed in anchoring the baffle wall 5 of a 55 typical boiler setting indicated generally at

6 and including baffle wall 5, bridge wall 7 and rear wall 8, the tube 9 of the boiler extending from the front header 10 through the baffle wall 5 and to the rear header 11.

In accordance with my invention a ditch 60 or trench 12 is provided lengthwise along the top of the bridge wall 7 which bridge wall while preferably a monolithic wall installed in plastic condition and vitrified may be of ordinary bonded brick or tile or of any 65 other suitable or preferred construction. Temporary supporting means comprising in this particular instance a strip of wood 13 is arranged lengthwise through the channel or ditch 12 resting upon the bottom thereof and the baffle wall 5 is then installed in a 70 plastic condition about the tubes 9 between temporary forms or against the flame plate where such plate is employed and down into the ditch or channel 12 and upon the upper 75 surface of the anchoring or supporting strip 13.

To provide clearance between the sides of the channel or ditch 12 temporary positioning strips 14 of card board, wood or the like are arranged therebetween. After installation, the plastic fire brick baffle is dried out by a slow fire to remove the moisture and the heat is then gradually increased to bake 80 the plastic material and vitrify the same 85 forming a jointless one-piece self-supporting baffle. As the baffle becomes self-supporting the temporary anchoring or supporting strip 13 and the temporary positioning strips 14 are burned out or at least contracted or 90 shrivelled up, providing clearance about the entire lower edge of the baffle wall, along the bottom and up between the sides of the adjacent sides of the bridge wall. This clearance permits the expansion and contraction resulting from the intense heating and fluctuating temperatures to which the 95 walls are subjected, without cracking, breaking or other injury to the baffle or bridge wall.

While the strip 13 is shown as being of substantially the width of the baffle wall 5 it may be of greater width or otherwise dimensioned as desired. The invention is especially suited for anchoring a baffle wall 100 installed in plastic condition and baked into a one-piece solid wall and I have therefore described the invention in that connection. I do not however intend thereby to limit 105 the invention in anyway to use in connection 110

with baffle walls or to use only where the wall is constructed of a plastic fire brick material as described. The baffle wall may be otherwise formed and as already pointed out the bridge wall may be formed of the same material and have the same coefficient of expansion as the baffle wall or it may be of different material and have a different coefficient of expansion. The temporary supporting and positioning strips may be of other material than wood or card board within the scope of my invention and they may be completely destroyed or only contracted or shrunk or otherwise displaced to provide the desired clearance about the bottom of the wall.

In addition to permitting expansion and contraction of the walls and tubes without injury, the clearance about the lower edge of the baffle wall permits that sagging of the boiler tubes which is practically impossible to prevent and which without such a joint would result in injury to the wall. The positioning strip 14 may be relatively thin as compared with the strip 13 because the expansion up and down is considerably greater than the transverse expansion.

In the embodiment shown in Figure 2 the baffle wall 20 is inclined forwardly slightly instead of being arranged substantially vertical as shown in Figure 1.

I claim:

1. The method of constructing a wall which comprises making all points of support for one surface of the wall temporary to temporarily anchor the wall until self-supporting and when self-supporting freeing the entire surface of the wall anchored by said temporary anchoring means.
2. The method of constructing a wall which comprises anchoring same temporarily upon another wall until self-supporting, and when self-supporting freeing the entire anchored portion of said wall to provide a clearance between it and the other wall.
3. The method of constructing a wall which comprises temporarily anchoring same until self-supporting and when self-supporting freeing the entire bottom of the wall.
4. In combination, a support, a wall and

temporary anchoring means between the wall and support, said temporary anchoring means being adapted to free the entire bottom of the wall to provide clearance between all points of the wall and said support.

5. In combination, a wall, a second wall anchored thereon, temporary anchoring means between said walls, said temporary anchoring means being adapted to free the entire anchored portion of said second wall to provide clearance between said walls.

6. In combination, a bridge wall, a ditch lengthwise along the top thereof, temporary supporting means in said ditch and a plastic fire-brick baffle wall anchored in said ditch and upon said temporary supporting means.

7. In combination, a bridge wall, a ditch lengthwise along the top thereof, temporary supporting and positioning means along the bottom and sides of said ditch and a plastic fire-brick baffle wall anchored in said ditch against said temporary supporting and positioning means.

8. In combination, a bridge wall, a strip of wood there along, a plastic fire-brick baffle wall anchored upon said strip of wood, said anchoring strip being destroyed by the heat applied in baking the baffle wall to provide clearance and permit expansion of the wall without injury.

9. In combination, a support having a recess therein, temporary anchoring means in said recess and a wall anchored in said recess and upon said temporary anchoring means.

10. In combination, a wall, a second wall anchored thereon, a temporary anchoring member between said walls, said first wall overlapping said temporary anchoring member and a portion of said second wall.

11. In combination, a wall, a support, a plurality of tubes extending from one side of the wall to the other and temporary anchoring means for said wall, said temporary anchoring means being carried by said support and extending without interruption along the wall in a transverse direction with respect to said tubes.

In witness whereof, I hereunto subscribe my name this 7th day of December, 1922.

WILLIAM A. L. SCHAEFER.
